UNITED STATES PATENT OFFICE.

CHARLES B. ORR, OF CHICAGO, ILLINOIS, ASSIGNOR OF ONE-THIRD TO SAMUEL V. WELLS AND ONE-THIRD TO ALPHONSO S. CROSBY, BOTH OF CHICAGO, ILLINOIS.

SHOW-CASE.

1,145,261.

Specification of Letters Patent.

Patented July 6, 1915.

Application filed December 23, 1912. Serial No. 738,131.

To all whom it may concern:

Be it known that I, CHARLES B. ORR, citizen of the United States, residing at Chicago, in the county of Cook and State of Illinois, have invented certain new and useful Improvements in Show-Cases, of which the following is a specification.

My invention relates to improvements in show cases, and particularly to such cases in which the walls or sides are composed of glass or marble, in whole or in part.

The especial object of the improvements embodied herein is to produce a show-case for articles of food which require refrigeration for proper preservation, in which the contents will be clearly visible to the customer, and readily accessible to the clerk without requiring the opening of doors.

A further object is to provide a sanitary show-case, in that all the exposed parts are of non-absorbent material and are so designed and combined as to be readily disassembled and thoroughly cleaned.

A still further object is to construct a show-case in which the cold-air produced by suitable refrigerating means connected therewith will be effectively circulated throughout the case while any heat in the articles placed in the case will be permitted to freely escape.

A still further object of the improvements embodied herein, is to provide a show-case of handsome appearance, and one in which is combined a small counter convenient for handling, cutting or wrapping the articles removed from the show or storage chamber.

Other objects of general utility are served by my invention which will be apparent to those skilled in the art.

In the accompanying drawings, I have illustrated a preferred embodiment of my invention in the following views:

Figure 1 is a vertical transverse section through my improved show case; Fig. 2 is a sectional detail showing the manner of connecting the front plates with a supporting bracket; Fig. 3 is a sectional detail showing the means for fastening the front and division plates together; Fig. 4 is a sectional detail showing the manner of connecting the top plates with a division plate; Fig. 5 is a sectional detail showing the connecting means between the end of a top-plate and a vertical end-plate; Fig. 6 is a sectional detail of the connection between the lower

edge of a division plate and the bottom flange members, and Fig. 7 is a sectional detail at the lower front margin of an end plate and its supporting flange member.

Referring to the details of the drawing, the numeral 8 represents the base of my improved counter, the same being preferably built of marble, cement, slate, or the like. Along the rear edge of the base is a refrigerating chamber, 9, the frame and walls 9^a of which are constructed of any suitable material and in any approved manner adapted to furnish the required strength and insulating qualities. Within the chamber 9 are arranged the refrigerator pipes or coils 10, which are supported by suitable brackets 10^a. The walls 9^a support a marble slab 11, which serves as a counter for use by the clerk in handling the articles removed from the show-case. If desired, this counter may have its lower surface exposed to the direct influence of the refrigerating chamber 9, so that it may be kept at a low temperature.

The show-case proper, is built up of glass plates which form the front, top, end and division walls, all of which are connected and braced by metal members, as will now be described. Assuming a show-case of twenty or more feet in length, the front wall will be composed of several glass plates 12, the top of a like number of glass-plates 13, and end walls of glass plates 14, and the partitions or division walls, of glass plates 15. The front and top plates are rectangular in form with straight edges on all sides, but the end and division plates are cut to form a curved edge 15^a, at the upper and inner corner of the case. At suitable intervals, I place within the case, brackets 16, the base 16^a of which rests upon and is secured by screws to the case bottom 8, the vertical portion 16^b supports the front wall plates 12, and the top member 16^c supports the top plates 13.

Referring to Fig. 2, it will be seen that the vertical portion 16^b of the bracket, 16, straddles the joint between the vertical edges of two of the plates 12, and is tapped to receive screws 17 which pass through flat metal straps 18 overlapping the edges of the plates 12, so that when the screws 17 are tightened, the margins of the glass plates 12 will be firmly clamped between the strap 18 and the bracket 16.

Referring to Fig. 3, which shows the

method of connecting a division plate 15 with two front wall plates 12, it will be seen that 18^a represents a flat metal strap similar to the strap 18 but not so heavy, 5 which bridges the joint between the edges of the plates 12, and which is pierced by holes to receive the screws 17^a which enter bosses 19^a extending outwardly from the clip base 19 between the adjacent edges of the plates 10 12. The base 19 is secured to the bottom of the right-angled clips 20, the flanges of which embrace the opposite sides of the plate 15. The connections between the angle-clips 20, and the plate 19, are made by 15 screws which pass through suitable slots within clips 20 and engage tapped holes in the plate 19, thus providing for adjusting the clips to fit glass of varying thickness, this arrangement being identical with that 20 shown in Fig. 6 in connection with other clips.

Referring to Fig. 4, it will be seen that the abutting margins of two top plates 13 are connected and supported by an angle-bracket 21, which in turn is connected with 25 two angle-clips 22, by the screw and slotted arrangement above described in connection with the clips 19 and 20.

In Fig. 6, the lower margin of the glass 30 plate 15, is shown clamped by angle-clips 24, in which are slots 24^a to receive the screws by which said clips are adjustably attached to the plates 25, the latter having threaded holes to receive the attaching 35 screws.

The reference numeral 26 represents an angle or corner bracket which is fitted to the outer corners of the top plate 13, and receives the screws which connect the clips 40 22, in the manner described in connection with the bracket 21, with which it differs only in that the bracket 26 has two vertical walls, while the bracket 21 has but one. The lower margin of the end-plates 14, are 45 held by a clip 27 which is screwed to the base 8 by screws 28^a, and by a second clip 28 which fits against the inner marginal wall of the plate, 14, and is adjustably connected with the clip 27 by screws 28^a.

50 It will thus be seen that I have provided a series of clips for clamping the margins of the glass plates which constitute the walls of my improved show case and that I have provided for inequalities in the thickness 55 of these plates by having at least one of a pair of complementary clips adjustable relative to the other.

It will be understood that the brackets or braces 16 will be placed at such intervals 60 as to effect the desired strength in the finished show-case, while their shape or design is such as to occupy but little of the space within the show case.

In the use of my improved show-cases, it 65 has been found that notwithstanding the

opening along the edges 15^a but little of the cold air from the refrigerator chamber 9 escapes to the atmosphere, owing to the greater specific gravity of said air, the course of circulation being indicated by the 70 arrows in Fig. 1. The constant pressure of the cold air within the case also serves to effectively exclude flies from the case. If there should be any latent heat in the meat or other articles placed in the case, it will 75 rise to the top of the latter, and escape at the rear opening at a point just below the top plates 13.

It will be understood that the clips 20, 22, 24 and 28 extend the full length or width 80 of the plates they embrace, except where their ends abut, in which case one of the plates is cut off to prevent the overlapping which would otherwise occur.

Having thus described my invention what 85 I claim as new, is:—

1. A device of the kind specified comprising an elongated display case consisting of a top wall or counter, a front wall, a bottom arranged in a plane parallel with said top 90 or counter and of greater width than the same, and dividing walls arranged at substantially right angles to said front wall, and a compartment disposed at the rear of and parallel to said case and open to 95 and communicating with the same along its side facing said case.

2. A device of the kind specified comprising an elongated display case consisting of a top wall or counter, a front wall, a bottom arranged in a plane parallel with said top 100 or counter and of greater width than the same, and dividing walls arranged at substantially right angles to said front wall, and a compartment disposed at the rear of and parallel to said case and open to 105 and communicating with the same along its side facing said case, said compartment having its top arranged in a horizontal plane parallel to and below the plane of the top of 110 said case.

3. A display case consisting of a top or counter, a vertical front wall disposed in the plane of the forward edge of said counter coextensive therewith, a bottom arranged in a plane parallel with said counter and of greater width than same, and a plurality of dividing walls arranged at substantially right angles to said front wall and extending rearwardly therefrom, the rear ends of the upper edges of said dividing walls terminating in substantially the vertical plane of the rear edge of said counter, and the lower edges of said dividing wall terminating at substantially the vertical plane of the rear edge of the bottom of said case. 115 120 125

4. A display case consisting of a top or counter, a vertical front wall disposed in the plane of the forward edge of said counter coextensive therewith, a bottom arranged 120 125

in a plane parallel with said counter and of greater width than same, and a plurality of dividing walls arranged at substantially right angles to said front wall and extending rearwardly therefrom, the rear ends of the upper edges of said dividing walls terminating in substantially the vertical plane of the rear edge of said counter, and the lower edges of said dividing wall terminating at substantially the vertical plane of

the rear edge of the bottom of said case, and having their upper corners cut away in an arc struck from the adjacent corner of said dividing wall.

In testimony whereof I affix my signature 15
in the presence of two witnesses.

CHARLES B. ORR.
